UNITED STATES PATENT OFFICE.

JOSEPH ROSS, OF NEW YORK, N. Y., ASSIGNOR TO HENRY J. GAISMAN AND FERDINAND S. M. BLUN, OF SAME PLACE.

DESIGN FOR A BUCKLE-FRAME.

SPECIFICATION forming part of Design No. 33,455, dated October 30, 1900.

Application filed September 28, 1900. Serial No. 31,449. Term of patent 7 years.

To all whom it may concern.

Be it known that I, JOSEPH Ross, a citizen of the United States, and a resident of New York city, borough of Manhattan, State of New York, have invented and produced a new and original Design for a Buckle-Frame, of which the following is a specification, reference being had to the accompanying drawings, forming part hereof, wherein—

- 5 ◦ Figure 1 is a face view of a buckle-frame embodying my design, and Fig. 2 is a cross-section on the line $x-x$ in Fig. 1.
- As shown in the drawings, the leading or material feature of my design consists in the
- 5 configuration of a buckle-frame in which the outer member or cross-bar is convex on its outer edge and concave on its inner edge, the side bars having their inner edges convexly curved and their outer opposed edges curved inwardly.

The letter A in the drawings indicates a buckle-frame the cross-bar a of which at its outer edge a' is convexly curved and its inner edge a'' is concave. The side bars b have their inner edges b' curved convexly and their outer edges b'' curved inwardly, and the forward or outer portion of the buckle-frame adjacent to the cross-bar a is wider than the inner portion of the frame adjacent to the cross-bar c .

I claim—

The design for a buckle-frame, substantially as shown and described.

JOSEPH ROSS.
